APPARATUS FOR ELECTRODEPOSITING
METALS

Roy Werrett, Cam, England, assignor to R. A. Lister & Company Limited, Dursley, Gloucester-shire, England, a British company

Application January 28, 1942, Serial No. 428,520
In Great Britain December 5, 1940

1 Claim. (CL 204—272)

This invention relates to the electrodeposition of metals on articles of the type (hereinafter referred to as the type described) having inner and outer faces, and apparatus therefor. Such articles may be tubular, or cylindrical, or may have the form of a container.

It is sometimes desirable to deposit a metal on the entire outer surface as well as on the entire inner surface of an article of cylindrical form, or on part of the outer surface and the entire inner surface, or on part of the inner surface and the entire outer surface, or on parts of both surfaces, and an important object of the present invention is to facilitate and expedite such electroplating operations, and to provide an improved construction of electroplating apparatus for that purpose.

According to the invention, there is provided apparatus for electrodepositing metal on an article having inner and outer faces to be plated, comprising a jig constituting a cathode, an inner anode arranged to lie within, and an outer anode arranged to lie surrounding the outside of the article for use simultaneously in plating its inner and outer surfaces, which jig is a structure of U-shape having an aperture in the middle of the base section thereof, means extending through said aperture for suspending the inner anode from and insulating it from the upper part of the jig, means for suspending the outer anode from and insulating it from the lower part of the jig, an annular block constituting a combined continuity and supporting member, on the upper side of which the article to be plated can be seated, and suspension means for securing said block to the base section with the upper end of the article in electrical contact with the cathode.

The outer anode may be provided with a three-point suspension from the jig, one of which points constitutes a terminal.

One form of apparatus according to the invention is illustrated by way of example in the accompanying drawings, wherein:

Figure 1 is a vertical sectional elevation showing one form of electroplating apparatus according to the invention;

Figure 2 is an elevation thereof, partly in section, as viewed from the left-hand side of Figure 1, but with one vertical wall of the jig removed, and

Figure 3 is an under plan view of the apparatus.

Like reference characters designate like parts throughout the several views.

Referring to the drawings, an article to be plated is suspended in the electrolyte of an elec-

troplating bath by means of a device known in the trade as a jig which functions as a cathode, which jig is a U-shaped structure that is designated generally 42, and is rectangular in plan and has two vertical walls 44, 46 and a bottom wall 48 having a rectangular aperture 50 in the middle thereof. The article to be electroplated may be a one-piece cylinder or a cylinder divided axially into two or more parts. As illustrated, the article 52 is a cylindrical journal-bearing that is divided longitudinally into two halves and has an external flange 54 at its upper end, which cylinder is supported, as described hereinafter, by the jig 42. In order to plate the inside and outside peripheral surfaces of the body of the two-part cylinder evenly and simultaneously, a two-diameter inner anode 56, 58 extends into the cylinder, and a second anode 60 surrounds the outside of it.

The inner anode 56, 58 is circular as viewed in plan, its part 56 of larger diameter constituting the head lying wholly within the article 52, and the part 58 of lesser diameter extending upwards from the head through the aperture 50 to restrict its free cross-sectional area, the lower end 62 of the head being bevelled. This inner anode 56, 58 is carried by a stem 64 having four radially arranged ribs or fins 66, which are shouldered at the top and seated on a rectangular piece of insulation 68 that is carried by the walls 44, 46 of the jig at the top thereof. These walls have each a perforated lug 70 for connection to a current-supply member. A lead-in member 72 is connected at 73, as by brazing, to the upper end of the stem 64.

The outer anode 60 is provided with a three-point suspension from the jig 42, from which it is insulated. One of these points of suspension constitutes a terminal and comprises a nut-equipped bolt 74 that extends through a lug 76 formed on the outside of the bottom wall 48 of the jig, and through a radial arm 78 of the outer anode 60. An insulating sleeve 80 is arranged between this arm 78 and the base 48 of the jig, and a second insulating sleeve 82 is provided around the bolt 74 above the lug 76 at a hole 83 in the wall 46 of the jig. A lead-in member 84 for the outer anode 60 is secured to the top of the bolt 74 by a nut 86, a collar 88, and a washer 90 being provided between the top of the sleeve 82 and the lead-in member 84. By tightening the nut 86 at the top of the bolt 74 and a nut 92 at the bottom thereof, the arm 78 of the outer anode can be firmly secured in position and good electrical contact can be made between it and the lead-in member 84. The

outer anode 60 has also two additional radial arms 94, 96, each of which is secured to, but insulated from, the bottom wall 48 of the jig by a nut-equipped stud 98 secured in the lower end of an insulating sleeve 100, whereof the upper end is secured to the wall 48 by a stud 102. As viewed in plan the three arms 78, 94 and 96 of the outer anode 60 are arranged in the form of a Y and firmly detachably secure the outer anode 60 in spaced relation with the article 52. This anode 60 may be cylindrical, but as illustrated it has at its upper end an inwardly-directed flange 104 which extends toward the article 52.

The article 52 to be plated may be suspended from the jig 42 constituting the cathode in any convenient manner so as to be in electrical connection with the jig. As illustrated, the suspension means comprises an annular member 106 which constitutes not only a supporting member, but also a continuity member for the article 52. This member 106 has its top face level with the bottom face of the outer anode, has a chamfered lower end 108, and is suspended by metal arms or pins 110 from an annular metal block 112, preferably composed of lead, having a rectangular aperture 113, which may be secured to the base 48 in any convenient manner; a rebated spacing piece 114 having a rectangular aperture 115 is shown provided between the rebated upper portion of the block 112 and the base 48, and the lead block 112 is welded or soldered to the spacing piece 114; the block 112 may be bolted and soldered in position, two studs being shown at 117, so that mechanical strength and good electrical conductivity are provided. The block 112 is provided with any convenient number of substantially vertical circulation ducts or gas-holes 118 that extend from a chamfered face 119 at the lower end thereof to the top face at a situation outside the spacing piece 114, which ducts serve for the circulation of the electrolyte, as the gas released by the current rises and circulates the electrolyte. The continuity member 106 is preferably composed of antimonial lead, while its two supporting arms 110 may be of a ferrous metal, e. g. steel, supported by horizontal pins 111 that extend through holes drilled for them in the block 112. These arms or pins 110 extend upwards in the gap formed between the two halves of the bearing which are to be processed and which are spaced slightly apart. Consequently the suspension means comprising these arms or pins 110 and the supporting member 106 does not interfere with the electroplating of the

inside or outside surfaces of the bearing. The chamfer 108 at the lower end of the continuity member 106 is preferably 45°; its function is to deflect the flow of electrolyte to the outside rather than to the inside of the article 52 so as to maintain an even rate of deposit on both the inside and the outside. Due to the construction of the apparatus as described, there is a greater obstruction in the flow of electrolyte to the outer surface of the article 52 than to the inner surface, so that this chamfer plays an important role.

The apparatus described above the anodes are provided with separate terminals by means of which current can be supplied from independent variable resistances, so that the rate of deposit may be varied and the actual thickness of the deposit controlled on either surface, the deposition taking place simultaneously on both surfaces from the same electrolyte.

The article to be plated may be of various shapes, for example its surfaces on which the deposits are to be made may be flat, concave, convex or angular.

I claim:

Apparatus for electrodepositing metal on an article having inner and outer faces to be plated, comprising a jig constituting a cathode, an inner anode arranged to lie within, and an outer anode arranged to lie surrounding the outside of the article for use simultaneously in plating its inner and outer surfaces, which jig is a structure of U-shape having an aperture in the middle of the base section thereof, means extending through said aperture for suspending the inner anode from and insulating it from the upper part of the jig, means for suspending the outer anode from and insulating it from the lower part of the jig, an annular block constituting a combined continuity and supporting member, on the upper side of which the article to be plated can be seated, the outer lower edge of which continuity member is chamfered and suspension means for securing said continuity member to the base section with the upper end of the article in electrical contact with the cathode, which suspension means comprises metal supporting arms that are attached to the continuity member and are adapted to extend each through a gap between spaced parts of the article supported thereon, said chamfered lower end directing electrolyte outwardly and upwardly around the outer surface of the article supported on said continuity member.

ROY WERRETT.
